UNITED STATES PATENT OFFICE.

HENRY BERLINER, OF NEW YORK, N. Y.

DESIGN FOR A SCARF-FASTENER.

SPECIFICATION forming part of Design No. 20,010, dated July 15, 1890.

Application filed May 31, 1890. Serial No. 353,859. Term of patent 3½ years.

To all whom it may concern:

Be it known that I, HENRY BERLINER, a citizen of the United States, residing at the city of New York, in the county and State of New York, have invented and produced a new and original Design for Scarf-Fasteners, of which the following is a specification, reference being had to the accompanying drawing, forming a part thereof, the figure shown being a front view of a scarf illustrating my design.

The feature of my design is the representation of a transversely-disposed ring or band C, composed of interlaced rib-like convolutions c, giving to the same a curved knotted appearance. Above the ring or band C

the scarf is disposed as a loop A, and below said ring or band are disposed flat parallel wings B. The body of the scarf is traversed by diagonal stripes D and E, of unequal width and bordered by wavy lines d, the ends 20 of the wings B converging to a point.

Having thus described my invention, what I claim as new, and desire to secure by Letters Patent, is—

The design for scarf-fasteners shown in the accompanying drawing.

HENRY BERLINER.
